UNITED STATES PATENT OFFICE.

QUINCY A. BRACKETT, OF PITTSBURGH, PENNSYLVANIA, ASSIGNOR TO WESTINGHOUSE ELECTRIC AND MANUFACTURING COMPANY, A CORPORATION OF PENNSYLVANIA.

MECHANICAL RECTIFIER.

1,311,489.

Specification of Letters Patent. Patented July 29, 1919.

Application filed April 29, 1915. Serial No. 24,745.

To all whom it may concern:

Be it known that I, QUINCY A. BRACKETT, a citizen of the United States, and a resident of Pittsburgh, in the county of Allegheny and State of Pennsylvania, have invented a new and useful Improvement in Mechanical Rectifiers, of which the following is a specification.

My invention relates to mechanical current rectifiers of the commutator type, and it has for its object to provide a device of the character described which shall be simple in design, efficient and reliable in operation and capable of adjustment for sparkless commutation when supplying current to a load of variable electromotive force.

In the rectification of alternating current by means of mechanically driven commutating devices, it is somewhat difficult to obtain sparkless operation because of variations in the time of zero current flow when contact should be made or broken within the device. This is especially true when operating with loads having a variable counter E. M. F. or when operating with alternating-current waves of other than the sine shape. By my invention, I am enabled to properly compensate for either of these conditions and to obtain substantially sparkless operation under widely varying circumstances.

Briefly speaking, my invention comprises a rotatable member driven in synchronism with the frequency of the alternating-current to be rectified and provided with a plurality of conducting arc members of various angular lengths corresponding to 180 electrical degrees or any desired portion thereof. A brush or brushes may be provided for closing the circuit with certain of said contact making arc members during the desired current wave, the specific contact making arc member employed depending upon the back electromotive force of the load and the connections being such that, when the load has a low back electromotive force, contact is made throughout the greater part of the current wave and, as the back electromotive force of the wave increases, contact is made for successively decreasing portions of the current wave.

In the accompanying drawing, Figure 1 is a diagrammatic view of a mechanical rectifier and its attendant circuits constructed in accordance with my invention; Figs. 2 and 3 are diagrammatic views of modifications of

the rectifier shown in Fig. 1, and Fig. 4 is a graph illustrating the operation of my invention.

Referring to the form of my invention shown in Fig. 1, a disk 5 is mounted to be driven by a motor 6 at half synchronous speed with respect to the frequency of alternating current from a source 7. Arc shaped conducting contact members 8 of different lengths are mounted on the face of the disk 5 and, symmetrically disposed with respect thereto, is a similar set of arc shaped conducting contact members 9. The contact members 8 are connected together by suitable means 10 and are also connected to a contact making arc member 11, for a purpose to be hereinafter set forth. In a similar manner, the contact members 9 are connected together by suitable wires 12 and also to a conducting arc member 13. Brushes 14 are mounted to bear respectively upon the contacting members 8 and are, in turn, connected to one terminal of the alternating-current source 7 through a suitable switching device 15 and a load 16, such, for example, as a storage battery. Similar brushes 17 are mounted to make contact with the contact members 9 and, in turn, are connected to the other terminal of the source 7 through a suitable switching device 18. Brushes 19 and 20 are provided to make contact with the contact members 11 and 13 and are connected together by a suitable wire 21. Each of the switching devices 15 and 18 comprises a movable bridging member 22 and suitable fixed contact members 23. The two bridging members 22 are connected to a rod 24 of insulating material and are normally maintained in the position shown by suitable means, such, for example, as a spring 25 which draws the rod 24 against a stop member 26. A core member 27 is mounted on the rod 24 and is associated with a solenoid 28 connected across the terminal of the storage battery 16.

Having thus described the structure of my invention, the operation is as follows: the disk 5 is rotated at such a rate that the length of the longest contact members 8 and 9 and also the contact members 11 and 13 corresponds to substantially 180 electrical degrees. Under these conditions, with a back electromotive force in the battery 16 of such small amount as to fail to move the core 27, the circuit will be closed for alter-

nate waves of the desired polarity from the source 7 through the battery 16, all three fixed contact members of the switching device 15, the brushes 14 and the contact members 8; the connecting wire 10, the contact member 11, brushes 19 and 20, with their connecting wire 21, the contact member 13, the connecting wire 12, all three of the contact members 9, the three brushes 17 and the switching device 18 to the other terminal of the source. During the remaining waves of the desired polarity, the connections will be the same except that the contact members 9 and 13 are replaced by the contact members 8 and 11 and vice versa. It will thus be seen that the current path is made and broken for each wave at four distinct points in series connection, namely, at the brushes 14, at the brush 19, at the brush 20, and at the brushes 17. Furthermore, the current at the brushes 14 and 17 is permitted to flow in three distinct branches and, accordingly, any tendency to harmful sparking is minimized because of the minute sub-division of the energy tending to produce sparks. When sufficient back electromotive force is developed in the battery 16 to energize the solenoid 28 to such a degree as to move the rod 24 against the spring 25 and to disconnect the right hand contact members 23 from the bridging members 22, the longest contact members 8 and 9 are removed from the circuit. Contact is therefore made only during shorter portions of each wave of the desired polarity because of the shorter length of the remaining contact members 8 and 9. This is the desired method of operation, as will be evident from a consideration of Fig. 4 wherein a line 29 represents an alternating-current wave of the desired polarity, the abscissa 30 representing the potential of the battery at the initiation of the charge and the abscissa 31 representing the potential of the battery at a later point in the charging. The optimum point for closing the circuit through the rectifier is at the point of zero current flow, which is the point where the rising voltage of the wave is exactly equaled by the back electromotive force of the battery. This point is at 32 at the initiation of a charge and is retarded as the charge progresses, as shown by the point 33 corresponding to the increased battery voltage 31. In like manner, the optimum moment for breaking the circuit occurs at 34 at the initiation of charge and is advanced as the charge progresses, as shown by the point 35 corresponding to a battery voltage 31. Ordinarily, little or no difficulty is experienced with sparking at the time of closing the circuit, and I have accordingly shown the leading ends of the contact members 8 and 9 as terminating on the same radial line but, obviously, if desired, the longest member may be made to close contact

with the brushes 14 and 15 in advance of the other members. When the voltage of the battery 16 reaches a still higher figure, the core member 27 moves the bridging members 22 to such an extent that only the left hand contact members 23 are engaged therewith, and only the shortest contact members 8 and 9 remain in circuit, with the result that only a small portion of the wave at the peak thereof is allowed to flow through the battery. Obviously, the number of contact members 8 and 9 may be increased to any desired degree in order to obtain more steps for the regulation of the minimum alternating-current voltage allowed to flow through the battery 16.

It is a well-known fact that the rate at which the ordinary lead storage cell can assimilate energy is much less toward the end of the charging period than at the outset thereof. Because of this fact, it is usual to "taper off" the charging rate, employing a much larger charging current at first than later on. By the structure shown in Fig. 1, a current path of relatively low brush resistance is provided during those periods when relatively large portions of each wave are rectified, that is to say, when the back electromotive force of the battery is low at the outset of the charging operation and, as the charge progresses with diminution of the charging current, the brush resistance of the current path may be increased.

Referring to the form of my invention shown in Fig. 2, a synchronous motor 6 is mounted to drive a cylindrical drum 36 upon which are mounted sets of commutating segments 37 and 40 of varying lengths and corresponding auxiliary segments 38 and 39. The segments 39 and 40 are mounted with an angular displacement of substantially 180° mechanically with respect to the segments 37 and 38. All the segments 37 and 38 are connected together by strap wires, as shown, in like manner, all the segments 39 and 40 are caused to act as a single conductive unit. A plurality of brushes 41 to 44, inclusive, are mounted to coöperate respectively, with the contact making segments 37 to 40, inclusive. The brushes 41 and 44 are connected, through a hand operable switch 45, to the terminals of the secondary winding 46 of a transformer 47, the primary winding 48 of which is connected to a suitable source of alternating current 49. The brushes 42 and 43 are connected together by a bond wire 50 and a suitable load, such, for example, as a storage battery 51, is connected between the wire 50 and the mid point of the secondary winding 46. The synchronous motor 6 is designed to drive the drum 36 at such speed that the length of the longer segments 37 and 40 corresponds to nearly 180 electrical degrees.

Having thus described the structure dis-

closed in Fig. 2, the operation is as follows: with the switching device 36 in the position shown, the brushes 41 to 44 corresponding, respectively, to the longest of the segments 5 37 and 40, are connected to the secondary winding 46. Assuming a positive wave to start from the left hand terminal of the winding 46, it will pass through the switching device 45 to the left hand brush 41, 10 through the longest segment 37, thence through the strap wires to the segment 38, to the brush 42 and bond wire 50, and thence through the battery 51 to the secondary winding 46. As the segments 40 are 15 placed by 180° mechanically with respect to the segments 37 on the drum 36, they will be out of contact with the brushes 44 during the above-described period of current flow. During the succeeding alternating wave, 20 however, which will be positive at the right hand terminal of the secondary winding 36, the segments 40 and 39 will make contact with the brushes 44 and 43, respectively, and current flow will be permitted through the 25 right hand half of the apparatus. In this manner, alternating-current waves of both polarities will be so rectified that they will flow in the same direction through the storage battery 51 and will cause the voltage of 30 the latter to rise. With the rise of voltage in the storage battery, there will be brought about a retardation in the optimum time of closing the circuit and an advance in the optimum time for the opening thereof, as 35 shown in Fig. 4. In order to prevent sparking, therefore, the operator manipulates the switching device 45 so that the contact making segments 37 and 40 of medium length are connected to the secondary winding 46 40 at the proper time, through the middle brushes 41 and 44, with the consequent proper adjustment of the time of make and break. In like manner, when the voltage of 45 the storage battery is approaching a maximum, the switching device 45 is again manipulated so that the shortest segments 37 and 40 are included in circuit with their corresponding brushes.

Referring to the form of my invention 50 shown in Fig. 3, which is in many respects similar to that shown in Fig. 1, a disk 52 of insulating material is so mounted as to be driven by a synchronous motor 6 at half synchronism with respect to the frequency 55 of the alternating current to be rectified. A conducting member 53 is mounted on the face of the disk 52, and, arranged to coat therewith, are brushes 55—55, mounted to slide in a suitable fixed frame 56 which is 60 placed in front of the disk 52. Bell-crank levers 57 and 58 are mounted on suitable pivots 59 and 60, carried by the frame 56, and the bell-crank levers 57 and 58 are each connected to the core member 61 of a solenoid 62 connected across a storage battery 65

load 63. Alternating current from any suitable source is supplied by mains 64, one of which is connected directly to the brush 55 and the other of which is connected to the brush 54 through the load battery 63. 70 The operation of this device is as follows: at the initiation of charge, the voltage of the battery 63 will be low, the pull of the solenoid 62 will be weak and the core 61 will be drawn to its highest position by a 75 suitable spring 65, throwing the brushes 54 and 55 outwardly so that they make contact with the rotating member 53 throughout relatively long arcs, current flowing from the brush 55 to the member 53, thence 80 through the neck thereof to the brush 54 and through the battery 63. Each end of the contact member 53 subtends an angle of slightly less than 90°, with respect to the center of the disk 52, at the outermost arc 85 of travel of the brushes 54 and 55 and, therefore, when the disk 52 is driven at half synchronous speed by a suitable design of the motor 6, the circuit will be closed through the battery 63 during waves of one 90 polarity and open during waves of the other polarity. As the charge of the battery 63 proceeds, the voltage thereof will rise, the strength of the solenoid 62 will increase, the core 61 will be drawn down and the 95 brushes 54 and 55 will be gradually shifted toward the center of the disk 52, with consequent shortening of the arcs of contact with the member 53 and adjustment of the points of make and break in accordance with the 100 principles set forth in connection with Fig. 4.

While I have, for the sake of clearness, shown the contact making arc members in Figs. 1 and 3 as mounted on the face of a 105 rotating disk, it will be readily apparent to those skilled in the art that they may be mounted on the surface of a cylinder by suitable modification, without departing from the spirit of my invention, and a somewhat better design from a mechanical standpoint be secured. Furthermore, by a duplication of the contact making devices shown in Fig. 3 and by a suitable fixed phase relation between the two sets of contact making devices, both waves of alternating current may be rectified in the manner indicated in Fig. 2.

Throughout this case, I have described the operation of the moving rectifying member at half-synchronous speed but its operation will be equally satisfactory if any even multiple or fraction of synchronous speed be chosen, provided a proper number of suitably proportioned contacting segments be 125 employed.

For a rectifier adapted for general application, where operation on loads having no back electromotive force may be desirable, it is necessary that the longest contact seg- 130

ments in my device cover substantially 180 electrical degrees, but, if only battery charging operation is contemplated, the longest of the contact arcs need cover only so many 5 electrical degrees as correspond to the time during which the applied electro-motive force of the load is equal to, or exceeds, the minimum back electromotive force of the load.

10 When operating under heavy load, the capacity of a simple multiple-contact relay, such as is shown at 28 in Fig. 1, may be exceeded, and any suitable heavy-current control system may be employed, such for example, as a standard circuit breaker having its contacts in series with each brush, each circuit breaker being tripped by its own separately adjusted over-voltage coil.

While I have shown my invention in three 20 distinct embodiments thereof, I do not desire to be restricted to these embodiments but desire that only such restrictions shall be placed thereupon as are imposed by the prior art or are specifically set forth in the 25 appended claims.

I claim as my invention:

1. In a commutating rectifier, the combination with a rotatably mounted member, of means for rotating said member in synchronism with the frequency of the alternating current to be rectified, contact making means mounted upon said member and arranged to provide a plurality of contact making arc members of different angular 35 lengths, connections from said contact making means to one terminal of the source of alternating current to be rectified, means for periodically connecting any one of said contact making arc members to the other terminal of said alternating-current source, and a load in one of said connections.

2. In a commutating rectifier, the combination with a rotatably mounted member, of means for rotating said member in synchronism with the frequency of the alternating current to be rectified, contact making means mounted upon said member and arranged to provide a plurality of contact making arc members of different angular 45 lengths, connections from said contact making means to one terminal of the source of alternating current to be rectified, a load of variable back E. M. F. between the alternating-current source and the rectifier, and 50 means for periodically connecting the longest of said contact making arc members to the other terminal of said alternating-current source when the back E. M. F. of said load is at a minimum value and for periodi-

cally connecting shorter and shorter contact 60 making arc members to the alternating-current source as the back E. M. F. of the load rises.

3. The combination with a source of alternating current, of a commutating rectifier 65 comprising a rotatably mounted member, means for rotating said member in synchronism with the frequency of the supplied current, a plurality of contact making arc members of different angular lengths mounted upon said rotatable member, a plurality of fixed brushes, one of which is mounted to make contact with each of said contact making arc members, a connection from all of said contact making arc members to one 70 terminal of said source, a connection from the other terminal of said source to a switching device associated with said brushes, a load of variable back E. M. F. in one of said 75 connections, and means operated by the back E. M. F. of said load to adjust said switching device, whereby said last named connection is completed to various of said brushes in accordance with the voltage of the load.

4. The combination with a source of alternating current, of a commutating rectifier comprising a rotatably mounted member, means for rotating said member in synchronism with the frequency of the supply current, a plurality of contact making arc members of different angular lengths mounted upon said rotatable member, the longest of said arc members covering substantially 180 electrical degrees and the remaining arc 95 members diminishing in length therefrom by graded amounts, a plurality of fixed brushes, one of which is mounted to make contact with each of said contact making arc members, a connection from all of said contact making arc members to one terminal of said source, a connection from the other terminal of said source to a switching device associated with said brushes, a load of variable back E. M. F. in one of said connections, and means operated by the back E. M. F. of said load to adjust said switching device, whereby said last named connection is completed to the brush in contact with said longest contact making arc member when 100 said back E. M. F. is at a minimum value and is completed to shorter and shorter contact making arc members in accordance with increases in the back E. M. F. of the load.

In testimony whereof I have hereunto subscribed my name this 24th day of April, 1915.

QUINCY A. BRACKETT.
